WILLIAM C. KELLUM, OF SAN FRANCISCO, CALIFORNIA.

Letters Patent No. 71,019, dated November 19, 1867.

IMPROVEMENT IN ESCAPEMENTS FOR TIME-PIECES.

The Schedule referred to in these Letters Patent and making part of the same.

TO ALL WHOM IT MAY CONCERN:

Be it known that I, WILLIAM C. KELLUM, of San Francisco, county of San Francisco, State of California, have invented an improved Escapement for Time-Pieces; and I do hereby declare the following description and accompanying drawings are sufficient to enable any person skilled in the art or science to which it most nearly appertains to make and use my said invention or improvement without further invention or experiment.

The object of my invention is to provide an improvement in escapements used in time-pieces, and which consists, first, in attaching a return-spring to the detent-lever by a pivot, in such a manner that the two may be kept in adjustment by one spring. The detent-lever may be locked upon the escape-wheel by gravitation, when used in an upright or pendent time-piece. Also my return-spring may be kept in its adjustment upon the point of the detent by gravitation, whether attached at any point of the detent by pivots, or to any other part of the time-piece. A lock-lever is attached to the detent-lever, so that in case more than one tooth passes at once, this lever will catch the escape-wheel and force it to lock upon the detent-lever.

It also relates to an arrangement for banking, by which the balance-wheel is allowed to vibrate to a certain point in either direction, but not far enough to pass more than one tooth. This is effected, first, by means of a light spring, so placed that as the hair-spring uncoils, it forces it out so as to catch the banking-pin on the rim of the wheel; and secondly, by means of a lever, so placed as to be moved out and in by the expansion and contraction of the hair-spring, and which shall catch the banking-pin at a certain point.

To more fully explain my invention, reference is had to the accompanying drawings, forming a part of this specification, of which—

Figure 1 is a top view, showing the manner in which it banks by means of the spring.

Figure 2 is a top view, showing the banking by the lever.

Figure 3 is an elevation, showing the end of the banking-lever, with its pins.

Figure 4 is a side view of the detent-lever and its spring.

Figure 5 is a top view, also showing the lock-lever.

Similar letters of reference, in each of the drawings, indicate like parts.

A is the balance-wheel of the time-piece, and is actuated by the impulse-pallet e and the hair-spring B. On the rim of the wheel A is placed a small pin, a, which projects upwards in figs. 1 and 2. A light spring, E, is fastened to the post G, and bent as shown, so that when the balance-wheel would vibrate too far in that direction, so as to unlock more than one tooth of the escape-wheel, the spring B is uncoiled so far as to press E out sufficiently to intercept the pin a, thus forming a banking at that vibration. The post b is so placed as to support the end of E when the pin a banks at that point. In ordinary vibration, the pin a passes by the end of the spring E without touching. The second banking consists of the lever C, vibrating on the axis D. At the end of this lever is the plate F, having a slot cut through it, as shown in fig. 3. Two pins, c c, project downward from this lever, at such a point that they stand on either side of the outer coil of the hair-spring B. This, by its increase and decrease of size, moves the end of the lever C out and in, the pin a passing through the opening in F, in ordinary vibrations, but if the balance-wheel vibrates too far, the spring B coils more closely, thus drawing the plate F in so far that the pin a will bank against it. Either banking may be used, and both, if desired.

The escapement is constructed in the following manner: H H is the detent-lever, which turns on the staff h, and has on its extremity the adjusting-screw I, which locks the teeth of the escape-wheel at each impulse. i is the impulse of the balance-wheel, and carries the impulse-pallet e and unlocking-pin d. n is a lock-lever projecting from the detent H, so that if by any means I becomes unlocked, it will prevent the escape-wheel from turning. J J is a return-spring or lever, pivoted to the detent-lever at m, and kept in contact with it at the point n by means of the spring K, or it may be kept in contact at n, and the detent-lever may lock at I by gravitation, when used in upright or pendent time-pieces, without the spring K. The return-spring J may also be attached at some other point, instead of the detent-lever. g g are stops attached to the plate, and standing on either side of the detent-lever, so that it will lock the escape-wheel sufficiently. The set-screw I may be altered so as to keep the teeth of the escape-wheel adjusted as desired.

In working, when the balance-wheel makes a vibration to the left, the pin d comes in contact with the end of the spring J, and moves it and the detent-lever H away, so as to unlock the adjusting-screw I, thus allowing

a tooth of the escape-wheel O to pass, the impulse being given by the pallet e at the same instant. The pin d passes the end of J, and when the vibration is complete, returns and lifts the spring J, so as to allow d to pass without acting on the detent-lever. As the detent unlocks, it moves the lock-lever n into the space between the teeth of the wheel O, so that if the detent-lever did not return soon enough to catch the next tooth, the lever n would lock it and prevent more than one tooth passing. By this construction I am enabled to make an escapement which is a dead-beat, and the time-piece having it will rate exactly and absolutely perfect. It can never be made to gallop or pass more than one tooth at a time, as it will bank in both directions.

Having thus described my invention, what I claim, and desire to secure by Letters Patent, is—

In combination with the escape-wheel O, I claim the arrangement of the detent-lever H, springs J and K, lock-lever n, and adjusting-screw I, substantially as and for the purpose set forth.

In testimony whereof I have hereunto set my hand and seal.
